(57) **CLAIM**

The ornamental design for a rear center inside position lamp for vehicles, as shown and described.

DESCRIPTION

1. Rear center inside position lamp for vehicles

1.1 : Perspective

1.2 : Front

1.3 : Back

1.4 : Left

1.5 : Right

1.6 : Top

1.7 : Bottom

1.8 : Perspective

1.1 is a top, front, and right side perspective view of a rear center inside position lamp for vehicles embodying our new design; 1.2 is a front elevation view thereof; 1.3 is a rear elevation view thereof; 1.4 is a left side elevation view thereof; 1.5 is a right side elevation view thereof; 1.6 is a top plan view thereof; 1.7 is a bottom plan view thereof; and 1.8 is a bottom perspective view thereof.

1 Claim, 8 Drawing Sheets
